UNITED STATES PATENT OFFICE.

LUTHER L. KNOX, OF AVALON, PENNSYLVANIA, ASSIGNOR TO KNOX PRESSED & WELDED STEEL COMPANY, OF PITTSBURGH, PENNSYLVANIA, A CORPORATION

FURNACE-DOOR FRAME.

1,118,429.

Specification of Letters Patent.

Patented Nov. 24, 1914.

Application filed January 10, 1914. Serial No. 811,389.

To all whom it may concern:

Be it known that I, LUTHER L. KNOX, a citizen of the United States, and a resident of Avalon, in the county of Allegheny and State of Pennsylvania, have invented a new and useful Improvement in Furnace-Door Frames, of which the following is a full, clear, and exact description, reference being had to the accompanying drawings, forming part of this specification, in which--

Figure 1 is a view partly in front elevation and partly in vertical section of a furnace door frame embodying my invention; and Figs. 2 and 3 are sections taken, respectively, on the line II--II and III--III of Fig. 1.

My invention has relation to furnace door frames, and more particularly to hollow water-cooled sheet metal frames.

The object of my invention is to provide a frame of this character, which is simple in construction, in which the welded connections are located at a distance from the door opening through the frame, and which is formed in sections so that in case of failure, any particular section can be removed and replaced without renewing or replacing the entire frame.

In the particular embodiment of my invention which I have illustrated in the accompanying drawings and which will now be described, the structure consists of the two vertical leg members 2 and the upper or lintel member 3. Each of the leg members has its body portion preferably formed of a single sheet or blank of metal bent into substantially the form shown in cross section in Fig. 3, and closed at the top and bottom by means of end plates 4, welded to the free edges of the blank. The free edges of the body-forming blank are welded together at the outer forward corner thereof, as indicated at 5. Preferably, each blank is formed with the hollow forward offset 6, whose inner vertical surface 7 acts as a door guide. Each leg is also preferably formed with the outwardly offset shoulder 8, at the top of the door opening, to form a support for the lintel member 3. This lintel member has its body portion formed from a single flat blank bent upwardly on parallel lines into substantially U-shape, and closed at the top by a plate or strip 9, welded or otherwise united to the free edges thereof. The sides of the body

thus constructed are formed by bending inwardly and backwardly the edges of the front member of the U-shaped blank, as shown at 10 in Fig. 3, and welding the edges of these inturned portions to the back member of the blank, as indicated at 11. The free edges 11^a of the back member of the blank extend freely beyond these inturned portions or flanges 10 and engage the rear portions of the legs 2, to prevent displacement of the member 3 relatively to the legs. Preferably, the rear sides of the legs are inset slightly, as shown at 12 in Fig. 3, to form seats for the projecting flanges 11^a.

Any suitable means may be provided for obtaining water circulation through the structure. For this purpose, I have shown each leg as having a supply pipe 13, extending downwardly therein from the upper end and terminating at a point near the bottom 75 of the leg. One of these supply pipes has a valved branch 14, which extends downwardly into the portion 3, and terminates at the lower portion thereof in a horizontal arm 15, provided with a series of spray perforations 16 at its lower side. Each of the legs is also provided with an outlet connection 17 at its upper end. The lintel portion also has an outlet connection 18, leading from the outer portion thereof and preferably into one of the outlet connections 17. The connections may be provided with suitable valves, as indicated, for controlling the circulation.

It will be noted that the portions of the members 2, 2 and 3, which form the edges of the door opening in the frame, are of continuous metal, free from seams, and that the welds are located at points distant from this opening. This feature, which is more fully described and claimed in my copending application Serial No. 811,388, filed of even date herewith, prevents any danger of the welded connections being injured or opened by contact with the charging apparatus or other tools introduced into the furnace through the door opening. It will also be readily understood that in case of failure of either of the leg portions or of the lintel portion, such portion can be removed and replaced by disconnecting the water-circulating connections and without the necessity of renewing the structure as a whole.

Various changes can be made in the details of construction and arrangement of the

parts, without departing from the spirit and scope of my invention. Thus, I may provide any suitable system of water-circulating connections; the lintel portion may 5 have either a straight or arched bottom; and various other changes may be made.

I claim:

1. A hollow water cooled furnace door frame, comprising a lintel portion and vertical leg members upon which the lintel portion is supported, said portion and each of said members being formed of sheet metal bent to form and welded, the welds in the leg members being at points distant from 10 the door opening between their lower portions, and the lintel portion having an integral bottom wall free from welds and forming the top of the door opening; substantially as described.
2. A hollow water-cooled sheet metal door frame, comprising vertical leg members and a lintel portion supported thereon, the lintel portion having a back plate formed with laterally extending portions which engage 15 the back of the leg members, substantially as described.
3. A furnace door frame, comprising separable lintel and leg members, the lintel member having its body portion formed 20 from a sheet metal blank bent into U-shape

and one member of the U having its edge portions bent toward and secured to the other member of the U to form the side portions of the body, substantially as described.

35

4. A hollow water-cooled sheet metal door frame having a lintel portion whose body is formed of a continuous sheet of metal bent into U-form, the edge portions of one member of the U being also bent at substantially 40 right angles and secured to the other member to form the side walls of the body, substantially as described.

5. A hollow water-cooled sheet metal door frame, having a lintel portion whose body is 45 formed of a continuous sheet of metal bent into U-form, the edge portions of one member of the U being also bent at substantially right angles and secured to the other member to form the side walls of the body, 50 and said other member of the U having its free edges extending laterally beyond said side walls, substantially as described.

In testimony whereof, I have hereunto set my hand.

LUTHER L. KNOX.
